Carroll Brooks Fry, 436 N. Roxbury Drive,
Beverly Hills, Calif.

Filed June 16, 1958, Ser. No. 51,381

Term of patent 14 years

(Cl. D14—6)

FIG. 1.

FIG. 2.

Figure 1 is a front view of a face plate for an electrical switching mechanism embodying my new design; and Figure 2 is a side view of Figure 1.

The lining on the drawing represents contrasting colored areas. The dominant features of my design reside in the portions shown in full lines.

I claim:

The ornamental design for a face plate for an electrical switching mechanism, as shown and described.
